(57) **CLAIM**

The ornamental design for a shoe stool, as shown and described.

DESCRIPTION

FIG. 1 is a front perspective view of a shoe stool, showing my new design;

FIG. 2 is a rear perspective view thereof;

FIG. 3 is a front elevational view thereof, the rear elevational view is identical;

FIG. 4 is a left side view thereof, the right side view is identical;

FIG. 5 is a top plan view thereof;

FIG. 6 is a bottom plan view thereof; and,

FIG. 7 is a front perspective view of the shoe stool in an exploded state.

The broken lines in the figures are for the purposes of illustrating portions of the shoe stool, which form no part of the claimed design.
